UNITED STATES PATENT OFFICE.

HARRY ROTHENBERG, OF RIDGEWOOD, NEW YORK, ASSIGNOR TO HENRY HYMAN & CO., INC., OF NEW YORK, N. Y., A CORPORATION OF NEW YORK.

PORTABLE ELECTRIC LIGHT.

Application filed September 19, 1918. Serial No. 254,706.

To all whom it may concern:

Be it known that I, HARRY ROTHENBERG, a citizen of the United States, and a resident of Ridgewood, in the county of Queens and 5 State of New York, have invented certain new and useful Improvements in Portable Electric Lights, of which the following is a specification.

The invention relates more particularly 10 to the switch or circuit controlling devices of portable electric lights of the character ordinarily held in the hand and lighted, as occasion may require, by the manual movement of means applied upon the exterior 15 casing of the device.

My invention resides more especially in a novel arrangement and construction of parts including a slide for completing the circuit between the lamp and battery, an escutcheon 20 on which said slide is mounted, and a spring held within the escutcheon and carrying at one end a button which is exposed through the escutcheon, said spring being formed with a cam surface to be acted on by an 25 inner portion of the slide for flexing said spring and moving said button to circuit closing position, and said spring independently of the slide being adapted to be flexed inwardly by external pressure applied 30 against said button, for completing the circuit. The slide or thumb piece will be made use of when a more or less permanent light is required, and the push button will be made use of independently of the slide when 35 it is desired to produce light flashes, as for signalling.

The invention will be fully understood from the detailed description hereinafter presented, reference being had to the accompanying drawings, in which:

Fig. 1 is a vertical section through one side portion of the casing of a portable electric light, said casing being equipped with circuit controlling means embodying my invention and the section being taken on the dotted line 1—1 of Fig. 2;

Fig. 2 is a central vertical section through the tubular portion of a flash light equipped with my invention;

Fig. 3 is a vertical section through a portion of the casing of the flash light having the circuit controlling means of my invention applied thereto, the parts being shown as having been operated to complete the 55 circuit, whereas in Fig. 1 the parts of the

switch mechanism are shown in normal position ready for use;

Fig. 4 is a detached inner face view of the escutcheon or switch casing, with the interior parts thereof shown in position; 60

Fig. 5 is a like view of the same with the circuit making spring omitted therefrom;

Fig. 6 is a detached outer face view or elevation of the switch or circuit controlling means embodying my invention, and 65

Fig. 7 is a transverse section through the same and a portion of the shell of the flash light, taken on the dotted line 7—7 of Fig. 2;

In the drawings, 15 designates a tubular 70 fibre or other insulating casing, and this casing may be of any suitable character adapted to receive a battery, reflector, lamp bulb and lens, which features I omit from the present drawing, since my invention resides in the circuit controlling devices 75 shown.

Within the casing 15 are two normally separated conducting strips 16, 17, the lower end of the strip 17 being for connection with 80 the negative pole of the battery, as usual, and the upper end of the strip 16 being carried upwardly to the upper edge of the casing 15 and adapted to be placed in electrical connection with the usual reflector. The 85 inner or upper end of the strip 17 is secured to one end of a metal escutcheon, switch casing or housing 18 by means of an eyelet or rivet 19, which also aids in securing the escutcheon upon the side of the casing 15 and places the strip 17 in electrical connection with said escutcheon. The inner 90 or lower end of the strip 16 is secured to the casing 15 by means of an eyelet 20 whose outer end is exposed within the escutcheon 95 or housing 18 but is not normally in electrical connection therewith. The housing or escutcheon 18 is rigidly secured in position upon the side of the casing 15 by the aforementioned eyelet or rivet 19 and by additional eyelets or rivets 21, said escutcheon or housing being formed with three apertured wings, as shown in Fig. 4, for receiving the outer 100 ends of the eyelets or rivets 19, 21.

Upon the exterior flat face of the escutcheon or housing 18 is mounted a thumb-piece or slide 22 preferably formed from sheet metal and having, at opposite sides, tongues 23 which are inserted through slots in the escutcheon or housing 18 and bent toward 110

each other, as shown in Fig. 7, not only to secure the thumb-piece or slide in position, but also to embrace one portion of a small plate 24 which is within the housing or escutcheon 18 and intended to move with the thumb-piece or slide 22. The plate 24 is illustrated in rear elevation in Fig. 5, and, as shown, is recessed in its opposite side edges to receive and interlock with the 10 tongues 23, whereby the plate 24 and thumb-piece or slide 22 become secured together. The main body of the plate 24 is flat and lies against the inner surface of the outer face of the escutcheon or housing 18, and 15 at one end, the upper end looking at the drawings, said plate 24 is depressed inwardly, as at 25, to form a V inwardly projecting cam surface. The end portions of the plate 24 cross the slots 26 through which 20 the tongues 23 formed on the sides of the thumb piece or slide 22 project, as shown in Fig. 5.

The escutcheon or housing 18 conceals the eyelet or rivet 20 by which the conducting 25 strip 16 is secured to the casing 15, and within the outer portion of said escutcheon or housing 18 is secured a spring 27 which is of the outline of the interior chamber of the escutcheon or housing 18 and is secured at 30 one end by an eyelet or rivet 28 to the outer wall thereof. The spring 27 extends from the eyelet or rivet 28 upwardly along the inner face of the plate 24 and at its upper end has secured thereto a push-button 29 which normally is exposed through an opening 30 in the escutcheon or housing 18. The spring 27 between the push-button 29 and eyelet 28 is bent inwardly, as at 31, to provide a space within which the V projection 35 of the plate 24 may slide, and the spring 27 at the upper end of said recess or space 31 is inclined correspondingly with the upper face of the projection 25 so as to coact with said projection as a cam surface or surfaces when the thumb-piece or slide 22 is moved upwardly toward the push-button 29. When the thumb-piece or slide 22 is pressed upwardly toward the push-button 29, the projection 25 on the plate 24 rides 40 upon the spring 27 and flexes the upper end of said spring inwardly, as shown in Fig. 3, so that the shank of the push-button 29 or the rivet securing the same to said spring may pass into electrical engagement with 45 the eyelet 20 and conducting strip 16, thereby completing the circuit through the lamp and battery. When the thumb-piece or slide 22 is moved downwardly from the position shown in Fig. 3 to that illustrated in Fig. 60 1, the spring 27 automatically returns to its normal position, its upper portion moving outwardly against the outer inner wall of the escutcheon or housing 18 and carrying the button 29 from the eyelet 20, there- 65 by breaking the circuit. The thumb-piece

or slide 22 has a tail-end 14 which sets outwardly from the outer face of the escutcheon or housing 18 and is adapted to pass over the outer end of the eyelet 28, as shown in Fig. 1.

The operation of the features illustrated in Figs. 1 to 7 inclusive will probably be fully understood from the foregoing description in so far as the movement of the thumb-piece or slide 22 is concerned; the 70 upward movement of the thumb-piece or slide 22 causes the plate 24 acting as a cam against the spring 27 to flex the upper end of said spring inwardly and complete the circuit through the eyelet or rivet 20, and when the thumb-piece or slide 22 is moved downwardly, carrying the plate 24 with it, the spring 27 is permitted to automatically retire from the eyelet 20 and in that way effect the breaking of the circuit. When a 75 more or less permanent light is required, the thumb-piece or slide 22 will be operated to complete and maintain the electric circuit, but when light flashes, as for signalling, or a temporary light, is required, the thumb- 80 piece or slide 22 may be ignored and the button 29 pushed in by the thumb so as to establish the circuit through the eyelet or rivet 20 and strip 16. I may thus utilize the thumb-piece or slide 22 for completing 85 the circuit or, independently of said thumb-piece or slide, I may complete the circuit by manual pressure against the outer end of the thumb-piece or button 29.

What I claim as my invention and desire 90 to secure by Letters-Patent, is:

1. A circuit switch-mechanism for portable electric lights comprising, in combination, a metal escutcheon having a thumb-piece slidably mounted on its outer face and a plate slidably mounted on its inner face and connected with said thumb-piece to slide therewith and having a cam-projection on one end, a plate-spring secured at one end to and within said escutcheon and being in 105 electrical connection therewith and having an inward bend affording a cam surface for cooperation with said projection in flexing the spring to circuit closing position, and a push-button secured to the free end 110 of said spring and exposed through said escutcheon and adapted when manually pressed inwardly to flex said spring to circuit closing position independently of said thumb-piece and plate connected therewith. 115

2. A circuit switch-mechanism for portable electric lights comprising, in combination, a metal escutcheon having a thumb-piece slidably mounted on its outer face and a plate slidably mounted on its inner 120 face and connected with said thumb-piece to slide therewith and having a cam-projection on one end, a plate-spring secured at one end to and within said escutcheon and being in 125 electrical connection therewith and hav- 130

- ing an inward bend affording a cam surface for cooperation with said projection in flexing the spring to circuit closing position and a push-button secured to the free end of said spring and exposed through said escutcheon and adapted when manually pressed inwardly to flex said spring to circuit closing position independently of said thumb-piece and plate connected therewith, 5
- 10 said escutcheon having parallel guide slots in its outer face and said thumb-piece having side fingers extending inwardly through said slots and folded toward each other upon said plate for securing the same against the inner surface of the escutcheon, and said 15
- 15 3. A circuit switch-mechanism for portable electric lights comprising, in combination, a metal escutcheon having a thumb-piece slidably mounted on its outer face and a plate slidably mounted on its inner face and connected with said thumb-piece to slide therewith and having a cam-projection on one end, a plate-spring secured at one end to and within said escutcheon and being 20
- 20 25 in electrical connection therewith and having an inward bend affording a cam surface for cooperation with said projection in flexing the spring to circuit closing position and a push-button secured to the free end of said spring and exposed through said escutcheon and adapted when manually pressed inwardly to flex said spring to circuit closing position independently of said thumb-piece and plate connected therewith, 30
- 35 said escutcheon having parallel guide slots in its outer face and said thumb-piece having side fingers extending inwardly through said slots and folded toward each other upon said plate for securing the same against the inner surface of the escutcheon, and said 40
- 40 45 plate having recesses in its opposite edges to receive and interlock the plate with said fingers, and said plate beyond said recesses being wider than the space between said slots.

Signed at New York city, in the county of New York and State of New York, this 29th day of August, A. D. 1918.

HARRY ROTHENBERG.
